XR D20,061 EX

RICHARD WILLM. BINNS, OF WORCESTER, COUNTY OF WORCESTER,
ENGLAND.

DESIGN FOR A VASE, JUG, OR EWER.

Design No. 20,061, dated July 29, 1890.

UNITED STATES PATENT OFFICE.

RICHARD WILLM. BINNS, OF WORCESTER, COUNTY OF WORCESTER,
ENGLAND.

DESIGN FOR A VASE, JUG, OR EWER.

SPECIFICATION forming part of Design No. 20,061, dated July 29, 1890.

Application filed April 21, 1890. Serial No. 348,918. Term of patent 7 years.

To all whom it may concern:

Be it known that I, RICHARD WILLIAM BINNS, director of the Royal Porcelain Works, Worcester, and a subject of the Queen of Great Britain, residing at Worcester, in the county of Worcester, in the Kingdom of Great Britain, have invented and produced a new and original Design for a Vase, Jug, or Ewer, of which the following is a specification, reference being had to the accompanying photograph, forming part thereof, and representing a side elevation of the jug, the rectangle and its contents below forming no part of the design.

The leading features of the design are as follows: the peculiar form of spout and mouth, the sides being bent inward somewhat, the back joining the handle, and the remainder of the mouth of the jug turned outward, the spout projecting considerably, the acanthus scroll forming the handle in part and leaving the handle proper a little above the junction of the latter with the body, independently joining the body, and continuing on the surface of the body round the face of the jug as a bass-relief, the beadings above and below this scroll, the acanthus-leaf ornaments in bass-relief above the upper beads and the semi-circular ornament on the lowest bead relieving the monotony of the side, the triple-expanding base with the flutings and leaf-carvings thereon, and the projecting bass-relief leaf-carving above on the lower part of the body of the jug, similar to but larger than the ones above the neck-beadings. The neck, body, and base are all round in horizontal

section, except where modified by junction with the handle and molded ornaments.

What I claim is—

1. The design for a vase, jug, or ewer herein shown and described, the same comprising a mouth bent in at sides with projecting spout, handle with acanthus-scroll clothing it in part and joining onto the foliate decorations round the lower part of the neck, the beading on each side this scroll, the semicircular ornament below the lower beading, the ordinary plain body, the triple-expanded fluted and ornamented base, and acanthus-leaf ornament above the base and above the neck-beading.

2. In the design for a jug herein described, the ornamentation of plain body, consisting of an acanthus scroll above on a conical part and joining the handles and bounded by beadings above and below, and acanthus-leaves below standing on beaded and conical base.

3. In the design for a jug herein described, the conical base, ovate body, and mouth curled up at sides, downward and outward at back, and outward at the lip.

In testimony whereof I have signed my name to this specification in the presence of two subscribing witnesses.

RICHD. WILLM. BINNS.
